ALARM CLOCK AND SWITCH

David L. Bohman, Ashland, Mass., assignor to
Telechron Inc., a corporation of Maine

Application March 7, 1946, Serial No. 652,727

9 Claims. (Cl. 58—19)

2

1

My invention relates to an alarm clock of the type which may operate both an audible and a silent alarm or two consecutive alarms of different volume or character, one of which is controlled by a switch.

My invention is applied to a clock driven by an alternating current motor and uses a vibrator buzzer operated by the motor field as one of the alarms. A switch is provided for operating the other alarm which may be any one of a variety 10 of electrically operated alarms, such as a flashing lamp, a radio receiver, a fan, a vibrator, etc.

An important feature of my invention is provisions for controlling these alarms independently of each other so that either or both may be 15 used as desired. Another important feature of my invention is provisions whereby the alarm switch may be turned on automatically at a selected time and turned off manually at any desired time thereafter. The same manual switch control mechanism has provisions for turning on and off the alarm circuit permanently or back to 20 automatic control, the latter reconditioning the mechanism for automatic operation. When the two types of alarms are both used consecutively, 25 the time period between the automatic operations of such alarms may be made adjustable to suit different people and situations.

The features of my invention which are believed to be novel and patentable will be pointed out in the claims appended hereto. For a better understanding of my invention, reference is made in the following description to the accompanying drawings in which Fig. 1 represents a perspective view of an alarm clock mechanism embodying my invention; Fig. 2 shows details of the vibrator alarm shutoff; Fig. 3 indicates the manner in which an automatic switch operating cam follower is flexed sideways by its cam and prevents automatic lifting of the cam lever and blocking of the cam; Figs. 4 to 8, inclusive, indicate different positions of the automatic and manual switch operating mechanism; Fig. 9 represents a face view of the clock; and Fig. 10 one way of making the time period between the successive automatic 45 operations of the two alarms adjustable.

Referring to Fig. 1, 1 represents the magnetic field core and 2 the energizing coil of a self-starting synchronous clock motor of the general type described in United States Letters Patent No. 1,495,936. Three (3) represents a gear casing containing the rotor and suitable reduction gears through which the terminal shaft 4 is driven. Shaft 4 drives the second hand shaft 5 of the clock through gear 6. The minute hand 7 and its

5 hollow shaft 8 are driven at one revolution per hour through back gears, one of which is indicated at 9. The hour hand 10 and its hollow shaft 11 are driven from the minute hand shaft 8 through back gears, one of which is indicated at 12 on a shaft 14. The back gear train 8 includes a friction clutch at 13 to facilitate setting the hands of the clock by means of the setting shaft 21 from the rear of the clock. The alarm cam shaft 15 and the alarm setting dial 16 are both driven from shaft 14 through a friction clutch 17 and gears 18, 19, and 20, preferably at one revolution in twelve hours. Hence the alarm setting dial 16 is driven at the same rate and in the same direction as the hour hand 10. A short pointer 10a on the hour hand shaft 11 cooperates with the alarm setting dial 16 to indicate on said dial the time at which the alarm is set to operate. The alarm cam shaft 15 and alarm setting dial 16 may be set independently of the clock hands by means of the alarm setting shaft 22 accessible from the front of the clock. When the minute and hour hands are set by turning shaft 21, the alarm setting dial 16 and alarm cam shaft 15 are 25 also set accordingly so as ordinarily to stay in a fixed time relation with the clock hands but may be set relative to clock time through the alarm set shaft 22. On shaft 15 are the audible alarm cam 23 and the switch operating cam 24. The audible alarm cam 23 has a depression 25 therein into which a cam rider extending from armature 26 drops when the depression 25 is opposite the cam rider extension. Twenty-six (26) is a resilient magnetic armature member rigidly secured 30 to the core 1 through a strap 27 at the left end of coil 2 and extending past the coil to the vicinity of a magnetic part 28 secured to the motor core at the right of the coil 2. The armature member is thus in flux shunting relation to the motor armature air gap of the core, which air gap is occupied by a reduced portion of gear casing 3 as shown in Patent No. 1,495,936, and when the coil 2 is energized by alternating current, the resilient armature member 26 tends to vibrate. 35 When the cam rider extension of this armature rests on the high portion of cam 23, the armature is slightly flexed upwardly and hence does not vibrate but when the depression 25 comes opposite the cam follower extension, the armature is released and it vibrates, and in so doing, its right-hand or free end knocks against part 28 and produces an audible alarm. An audible alarm 40 of this general character is described in United States Letters Patent No. 2,002,433 to Cowles. 45 The cam 23 rotates clockwise and is so shaped

as to raise the armature 26 out of the depression after a suitable alarm period as the clock runs following such automatic audible alarm operation. The armature 26 can also be raised out of the cam depression to silence the alarm prior to the time it would otherwise be raised by the cam, or it can be prevented from dropping in the cam depression entirely by means of a resilient hook member 28, extending under the right-hand free end of armature 26, when such hook member is raised by pushing in on the alarm setting shaft 22.

As illustrated, the shaft 22 has a double cone-shaped part 30 engaging a sloping under surface of the resilient hook member 28 near its free end such that when the shaft 22 and cone 30 are moved to the rear, hook 28 and armature 26 are raised to silent position as indicated in Fig. 2. As illustrated in Fig. 1, the shaft 22 is in its forward position, which will allow the audible alarm to operate at the time for which set, indicated by hand 10a on dial 16. When in the latter position, the double cone member 30 acts as a detent with a V-shaped depression in hook 28 to hold the shaft 22 in the longitudinal position illustrated in Fig. 1. When the shaft 22 is pushed to the rear to silent position as illustrated in Fig. 2, the V-shaped depression of hook 28 rests upon and presses against a larger diameter surface of cone member 30, which surface has a slight reverse cone shape. This firmly holds shaft 22 in this silent alarm position with a spacer 38a abutting against a rear bearing plate 31 for shaft 22. In the last-mentioned position, the gear 32 on shaft 22 is preferably demeshed from gear 18 to avoid unnecessary wear, since when such gears are meshed, shaft 22 is driven with the clockwork.

From the above description it is seen that the audible alarm may be used or not as desired, and when used, may be shut off manually as soon as desired, after it is started automatically and if not shut off manually, will be shut off automatically after a suitable time interval. This automatic operation will occur at a selected time as determined by the setting. The manual shut-off parts are designed to be firmly held in the positions to which adjusted. The setting and shutoff control are both actuated from the same thumb piece 22a on shaft 22 from the front of the clock.

The other cam 24 on shaft 15 has a rectangularly shaped depression 33 therein and cooperates with a cam follower lever 34 pivoted at 35 to participate in the operation of a switch mechanism consisting of three resiliently mounted contacts 36, 37, and 38. A manually rotatable shaft 39 also participates in the operation of this switch mechanism and has three positions established by a detent at 40 and marked on the front of the clock as "Auto" (meaning automatic), "Off" and "On." A thumb piece 39a on the front end of shaft 39, by means of which shaft 39 is positioned, has an arrow thereon which points to and indicates the rotary position of this manual switch operating shaft. Thus in the position represented in Fig. 1, the arrow points to "Auto" meaning Automatic, and when in this position, the cam 24 and lever 34 have automatic control of the closing of the lower contact 38 of the switch to the extent that such parts have control. When button 39a is turned to "Off" position, all switch contacts are open, cam lever 34 is held in a raised position, and cam 24 and lever 34 do not exercise any control. When button 39a is turned to "On" position, the switch contacts 36 and 37 are closed

and the cam 24 and lever 34 again have closing control of the lower contact. Due to the circuit connections generally used, it is immaterial whether contact 38 be closed or not in the "On" position of the switch.

An important feature of this joint automatic and manual control of the switch is the use of cam follower lever 34, which is made of sufficiently thin material as to be resilient in a sidewise direction, and a cam follower part 41 set at an angle to the rectangular slot 33 in the cam 24 so that the part 41 may be pushed out of the cam slot 33 in a sidewise direction as the cam rotates past part 41 without lifting the lever 34. The part 41 may likewise move into the slot from the side without lifting of the lever 34. In case the cam 24 is rotating clockwise as viewed in Fig. 1 when the part 41 is in slot 33, as will be the case following an automatic operation with the clock in normal operation, the part 41 will be pushed out of slot 33 on the rear side of the cam 24 as represented in full lines in Fig. 3. In case the cam follower part 41 is in slot 33 when the cam is set forward in the same direction to change the alarm time, the part 41 will likewise be pushed out on the rear side of the cam. In case the part 41 is in the slot 33 and the cam 24 is turned counterclockwise, the part 41 will be pushed out of the slot on the front side of the cam as represented in dotted lines in Fig. 3. Thus the cam 24 may be turned in either direction in an alarm setting operation so far as this cam is concerned without having the cam blocked by reason of cam follower part 41 being located in the rectangular slot having essentially radial drop and rise sides. The angular bend of part 41 may be in either direction. As shown, it has a bend of about 45 degrees to the front of lever 34. Instead, it could have a bend of about 45 degrees to the rear. The only difference would be in the direction it pushes out of the slot for a given direction of rotation of the cam. It is to be noted in Fig. 1 that the cam lever 34 is undercut at 42 adjacent part 41, so that the lever part will not engage with the periphery of the cam and prevent the sidewise disengagement of part 41 from the slot 33 in either direction. To prevent cam lever 34 dropping down to a position where it might not clear the periphery of the cam 24 in such sidewise movement, the lever has an upper hook projection 43 which engages with a stationary post 44 to limit the downward movement of lever 34. It is seen that so far as the automatic operation of lever 34 is concerned, by the clock operated cam 24, the cam will permit the cam lever to move from raised to lowered position but will not move it from lowered to raised position. The reason for this is that one purpose of the device is to turn on a radio program at a selected time automatically when the cam lever is lowered by closing certain contacts of the switch, and to avoid having the program interrupted by subsequent automatic opening of the switch contacts. The switching operation performed automatically by a lowering of lever 34 may be reversed manually when desired by manual turning of switch operating shaft 39 from automatic to off position, and such operation also lifts the cam lever 34 from its lowered to raised position.

The pivoted end of lever 34 carries a piece of insulating material having upper and lower sector-shaped arms 45 and 46 which move with the lever. The upper arm 45 cooperates with the resilient lower contact 38 of the switch. This contact is biased upwardly so as to normally

engage the center or intermediate contact 37, and the purpose of arm 45 is to press contact 38 downward to hold contacts 37 and 38 open when the cam lever 34 is in the raised position as shown in Fig. 1. When the lever 34 is lowered by reason of part 41 dropping into cam slot 33, arm 45 is retracted from contact 38 and allows it to close on contact 37. The lower arm 46 which is moved with lever 34 is positioned to engage with a finger 47 on the switch shaft 39 when the shaft is moved to or is in "Off" position. Such engagement positions the lever 34 to raised position, moves it to such position if it is not already in such position, and prevents its automatic movement from raised position. When switch shaft 39 is in the automatic position shown in Fig. 1, finger 47 is above arm 46 as shown in Figs. 4 and 5 whether the lever 34 be in the raised position, Fig. 4, or in the lowered position, Fig. 5.

Fig. 6 represents the position of finger 47 with shaft 39 in "Off" position and it will be evident that finger 47 in moving from "Auto" position, Fig. 5, to "Off" position, Fig. 6, will raise lever 34 and open switch contacts 37 and 38. The lever 34 is thus raised whether the cam follower 25 be in the slot 33 of the cam 24 or be shoved to one side of the cam as represented in Fig. 3. This comprises the means for manually lifting the cam lever 34 following an automatic lowering operation. When in "Off" position, Fig. 6, the rounded end of finger 47 engages the rounded end of arm 46 so that finger 47 may be rotated in either direction past arm 46, lever 34 turning on its pivot to allow this. When the switch shaft 39 is in "On" position, its finger 47 is below arm 46 in either the raised or lowered position of the latter as indicated in Figs. 7 and 8.

The upper resilient contact 36 is normally biased upwardly so as not to contact with the intermediate contact 37. However, contact 36 has a finger 48 extending downward therefrom, which is positioned to engage with the wedge surface 49 on the rear of a finger 50 secured on switch shaft 39, so that when the shaft is turned to "On" position as represented in Figs. 7 and 8, wedge surface 49 pushes rearwardly on finger 48 which bends contact arm 36 downward, so that its forward end contact engages with contact 37 as represented in Figs. 7 and 8. It is evident that the movement of contact 36 is controlled manually and never automatically. The resilient contact members are all supported by an insulated support at 51 a sufficient distance from their free contact ends to permit of the switching movements described, and provisions are made at the insulated support to connect the contact members to the circuits to be controlled. The contacts may be connected in a variety of ways to circuits and devices to be controlled. Either the upper or lower set or both sets of contacts may be used by the simple expedient of leaving a contact which is not to be used disconnected, or the corresponding contact may be omitted from the mechanism entirely without interfering with the proper functioning of the remaining parts.

One circuit connecting arrangement which may be used is represented in Fig. 1 where 52 represents a circuit plug outlet secured on and accessible from the rear of the clock and into which some electrical appliance to be controlled may be plugged. One side of such outlet is connected by wire 52a to one side of the same source 53 as is used to supply the electric clock motor field 2. The other side of outlet 52 is connected through

wire 54 to upper terminal 36 of the switch, and the center contact 37 of the switch is connected through wire 55 to the opposite side of source 53. so that when contacts 36 and 37 are closed, as they will be in the "On" position of switch shaft 39, the plug 52 is energized. Another connection from the lower side of plug 52 back to the source of supply which parallels the connection just described is available through wire 56, a contactor 10 57, wire 58, the lower contact 38 of the clock switch and through center contact 37 and wire 55 when contacts 37 and 38 are closed in response to an automatic clock operation. The contactor at 57 is of the intermittent opening and closing type operated by a bimetallic thermal strip 59 and a heater coil 60 which is connected at one end through wires 52a and 61 to one side of source 53 and has its other end 62 connected to the bimetal strip 59. Hence the heater coil is energized whenever strip 59 is connected to the other side of source 53 through clock contacts 36 and 37 or through contacts 37 and 38 and 57. Contacts 57 are normally closed when the heater coil 60 is not energized. Hence with clock contacts 36 and 37 open and contacts 37 and 38 closed, the thermal contact device will function to intermittently open and close the contacts at 57 and its own circuit and the circuit of any appliance plugged into socket 52. When the bimetal strip 59 is heated by coil 60, it bends upward to open contacts 57 and then cools to close such contacts. The intermittent thermal contactor is generally used when the circuit just described is used as an alarm circuit by plugging into socket 52 a lamp or a vibrator. A flashing lamp is desirable as an alarm to awaken deaf persons. It will be understood that as thus used the switch shaft 39 will be turned to the automatic position and the alarm time set to close switch contacts 37 and 38 at the time desired to awaken or otherwise notify the person so using the apparatus. Except for the power supply leads 53, the wiring described is preferably contained and concealed in the clock case.

In case the intermittent feature is not desired in the automatic alarm circuit, it may be omitted or simply short circuited by connecting the upper and lower clock contacts 36 and 38 together either permanently or as by a switch 63. As thus connected the switch clock is ideal for use with a radio receiver, as the same device may be used to turn the radio on and off manually as desired, as well as to turn it on automatically at a set time. The apparatus will not interrupt a selected radio program automatically, but a person may cut it off when desired by turning the button 39a to "Off" and when subsequently turned back to automatic from either the "Off" or "On" position, the apparatus conditions itself for automatic operation by lifting cam lever 34. When cam lever 34 has been pushed to one side of the cam 24 and is thus lifted, it springs back to normal position over the upper cam surface as soon as it is lifted above such surface, and as soon as finger 47 moves away from arm 46, the cam lever comes to rest with the cam follower part 41 resting on the periphery of the cam.

When connected as shown in Fig. 1, the heater coil 60 will be continuously energized when the switch shaft 39 is turned to "On" position and the plug 52 is energized. This does no harm. It simply holds the contacts at 57 open. Also as wired, the opening and closing of contacts 37 and 38 has no effect when the switch is turned to "On" position. As shown in Fig. 9, the alarm

button 22a and the switch operating button 39a are accessible from the front of the clock and are conveniently positioned at the 3 and 9 o'clock positions of the clock dial. It is evident from the foregoing description that the automatic audible buzzer alarm 28 associated with the field of the motor may be permanently cut off or temporarily cut off after being turned on automatically before it would otherwise be turned off by cam 23 by pushing in on the alarm set button 22a, and that both this alarm and the automatic electric alarm circuit may be set to operate at selected times by turning the button 22a when in the pulled-out position. It is to be noted that the shutting off of the buzzer alarm does not interfere with any automatic switching operation to be performed by the lever 34 and cam 24. Likewise, the electric alarm circuit automatically closed through contacts 37 and 38 may be used or not independently of the buzzer alarm by turning button 39a from "Auto" to "Off" and the circuit in question may be turned on and off as desired by turning button 39a between "On" and "Off." When subsequently turned to "Auto," the cam lever 39 is repositioned for automatic operation. The circuit which is closed automatically does not open automatically. Thus when this circuit is used to turn on a radio receiver at some selected time, the radio program is not interrupted in the middle of a desired program by automatic clock operation but may be turned off when desired manually.

Notwithstanding the independence between the two alarm release operating mechanisms, they are so designed as to be used together by first turning on a gentle alarm such as a flashing lamp or a radio receiver and, if this does not arouse the sleeper in a short time, then turning on the more persistent buzzer alarm. To this end the two cams 23 and 24 are so rotatively positioned on their common shaft 15 that as the shaft is turned clockwise by the operation of the clock, cam follower 41 of switch lever 34 will drop into slot 33 of its cam, say, ten minutes before the cam follower projection of armature 28 drops into slot 25 of cam 23. As thus used the procedure may be as follows: Upon retiring, the person using the clock sets both alarms to automatic and time sets the alarm to operate at the desired awakening time. When such time arrives, the electric circuit will be turned on automatically, thereby turning on a radio program, for example. If this awakens the sleeper within a short time interval, he may push in on button 22a so that the audible buzzer alarm will not operate. If the sleeper is not aroused by the first alarm, the buzzer alarm will sound in a short period of time and will continue to sound until shut off manually or automatically. The length of the cam slot 25 is such that the buzzer alarm will ordinarily sound automatically for about one-half hour. The electric alarm circuit may be opened manually at the will of the operator either before or at any time after the time the buzzer alarm would sound if permitted to do so. The cam shaft 15 preferably makes one revolution in 12 hours rather than 24 hours, since the device is intended to be used throughout the day and evening for automatically turning on selected radio programs or other electrical appliances at selected times with the buzzer alarm shut off, and a 12-hour cam may be set more accurately than a 24-hour cam.

The period of time between automatic operation of the switch and the turning on of the

7
8
buzzer alarm is primarily determined by the relative rotative positions of the cam slots 25 and 33 on shaft 15, and this is ordinarily set at the factory for, say, a ten-minute period. However, in some instances, the person owning the clock may desire to shorten or lengthen this period and change it from time to time, and provision may be made to accomplish this purpose in a relatively simple and inexpensive manner as follows: 10 Since the cam follower part 41 of cam 24 is set at about 45 degrees to the face of the cam, the time at which it will drop into the slot may be changed by relative sidewise movement of the cam and cam follower, while this will not change the time of drop-off at cam 23 because the cam follower projection of armature 28 is at right angles to the face of its cam. In Fig. 10 there is shown means for taking advantage of this situation for varying the period of time between the operation of the two automatic alarms. The cam shaft 15 is rotatively mounted in clock plates, one of which is shown at 84, to permit slight endwise movement of shaft 15 but not enough to interfere with the meshing of gears 19 and 32 20 when they are intended to mesh. Adjacent the periphery of cam 23 some distance removed from the cam follower part of armature 28 is a shaft 65 screw-threaded through clock plate 84 and having its rear end supported by rear plate 31 25 extending from the motor core structure and used also as shown in Fig. 2 to support the rear end of setting shaft 22. The front end of shaft 65 is recessed at 66 to embrace the peripheral edge of cam 23 and thus determines the endwise 30 position of cam shaft 15 during the time when the automatic cam operations occur. The rear end of shaft 65 may have a thumb nut or may have a screwdriver slot therein and may protrude from the rear of the clock case or be accessible 35 through an opening in the rear of the clock case for insertion of a screwdriver for turning the shaft 65 to screw it in or out and thus vary the endwise position of shaft 15.

As positioned in Fig. 10, the sloping cam follower 41 is about to drop off into the slot 33 in its cam 24 as the cam rotates in the direction of the arrow thereon. It is evident that with the cam 24 in the rotative position indicated, the cam follower 41 will drop in slot 33 if the cam be moved axially to the left about two-thirds of its thickness to the position indicated in dotted lines. However, such endwise movement of the cam shaft will not change the drop-off time with respect to armature 28 and slot 25 in cam 23 because here the cam follower extends at right angles to the cam. Thus it is evident that by screwing shaft 65 in and out by a small amount, the time period between the automatic drop-off operations at the two cams may be varied over a period of several minutes. The parts are preferably arranged so that the switch lever 34 operates automatically from about 5 to 30 minutes before the buzzer armature 28 operates with the approximate exact period adjustable to suit the user. This range of adjustability can be increased by arranging both cam followers at oblique but reverse angles to their cams. The apparatus may of course be arranged to select which type of alarm will operate first and to adjust the period between their automatic operations. The recess 66 has rounded shoulders so as to guide the cam 23 into the recess without difficulty when the cam slot 25 passes this point. The shaft 65 may be screwed endwise into place after the clockwork and cam shaft have been

assembled by rotating cam 23 so that its slot 25 is in alignment with shaft 65.

It will be evident that moving the normal position of cam lever 34 sidewise will accomplish the same purpose as endwise movement of cam shaft 15. Either of these expedients is generally easier to accomplish than attempting to rotate the cams relative to each other after the clock is assembled, both from the point of manufacture and for the user. The rear of the clock will carry instructions about shaft 65 to indicate which way to turn the shaft to lengthen and shorten the adjustable time period in question. This adjustable feature may be omitted without interfering with the remaining structure or its operation.

What I claim as new and desire to secure by Letters Patent of the United States, is:

1. An alarm clock combination comprising a clock, audible alarm means, an electric alarm circuit including a switch, a pair of automatic release mechanisms, both operated by said clock one for controlling operation of said audible alarm and the other for closing said switch, common means for adjusting said release mechanisms for the purpose of determining the time when the audible alarm will sound and the time the switch will be closed automatically, means for at will preventing the sounding of the audible alarm when it would otherwise sound, and means for at will preventing the closing of the switch when it would otherwise close in response to automatic clock operation, said two preventing means being independent of each other such that either or both the audible alarm and the switch may thus be operated automatically or prevented from operation by the clock at the times set for such operations.

2. An alarm clock combination comprising a clock, audible alarm means, an electric alarm circuit including a switch, a pair of automatic release mechanisms, both operated by said clock one for starting and stopping the operation of said audible alarm and the other for closing said switch, common means for adjusting said release mechanisms to determine the times when they will perform their automatic operations, manual means for at will preventing the automatic sounding of the audible alarm when it would otherwise sound and to stop its operation when sounding, manual means for at will preventing the automatic closing of said switch when it would otherwise close and to open the switch when closed, said two manual preventing means being independent of each other whereby either or both the audible alarm and the switch may thus be operated automatically, or prevented from operating automatically when they would otherwise so operate, and whereby the audible alarm may be silenced when sounding and the switch opened when closed independently of each other.

3. An alarm clock combination comprising a clock, an audible alarm, an alarm circuit including a switch, a pair of release mechanisms both operated automatically in response to the operation of said clock at predetermined adjustable times, one release mechanism controlling the automatic starting and stopping of said audible alarm and the other release mechanism controlling the automatic closing of said switch and being designed to prevent the automatic opening operation of the switch, and manual means for opening said switch and reconditioning the switch closing automatic release mechanism for subsequent automatic switch closing operation.

4. A switch and clock combination comprising a clock, a circuit including a switch having first and second positions, a rotary cam continuously driven by said clock, a pivoted cam lever riding on said cam as a cam follower for operating said switch and having first and second positions corresponding to the similar designated positions of said switch, said cam having a depression into which the contacting portion of said cam follower moves to cause the automatic operation of said switch and lever from said first to second positions, said depression being shaped so as to prevent the cam follower from riding out of said depression in a direction to return the lever and switch from said second to first positions, said cam lever being flexible in a direction at right angles to its switch operating movement and having a cam follower surface shaped so as to be pushed out of said cam depression in said right angular direction by said cam whereby the cam follower is prevented from blocking the continued rotation of said cam, and manual means for returning said lever and switch to their first positions.

5. A switch and clock combination comprising a clock, a switch therein having first and second operating positions, a cam follower lever for operating said switch between said positions and having first and second positions corresponding to the like designated positions of said switch, a rotary disk-shaped cam continuously driven by said clock and on the periphery of which the cam follower portion of said lever is adapted to ride, said cam containing a slot with substantially radial edges such that the cam follower will drop therein automatically in moving the lever from first to second positions but will not ride radially out of said slot to move the lever from second to first positions in response to the rotation of said cam, said lever being flexible in the axial direction of said cam and having a cam follower portion set at an angle of the order of 45 degrees to the axial direction of the cam so as to be flexed and pushed out of the depression sideways by the rotation of the cam, and manual means for returning said lever from the second position, either before or after being flexed sideways, to the first position in an unflexed condition.

6. An alarm clock combination comprising a clock, an audible alarm, an electric alarm circuit including a switch, a pair of automatic release means operated by said clock one for releasing the audible alarm to permit it to sound, and the other for closing said switch, means for adjusting the time of day at which said automatic operations will be performed, and other means for adjusting the time period between said two automatic operations.

7. An alarm clock combination comprising a clock, a pair of rotary disk-shaped cams mounted on the same shaft and driven by said clock, a pair of cam followers bearing against said cams, means operated by said cam followers for controlling the automatic operations of separate alarms, means for adjusting the rotary position of said cam shaft relative to the clock for determining the time of day the automatic alarm operations will be performed, said cam followers being set at different angles across their respective cams, and means for adjusting the relative positions of said cam shaft and cam followers in a direction endwise of the shaft whereby the time period between the automatic alarm operations performed by said cam followers may be adjusted.

8. In combination with a clock, an alarm circuit including a first switch, movable means operated by said clock at a predetermined adjustable time for automatically closing said switch, said means being incapable of automatically opening said switch, manual means associated with said switch and having first, second, and third positions, the first position permitting the automatic closing operation of said switch, the second position preventing the automatic closing operation of said switch, a second normally open switch in parallel relation with said first switch in said circuit, the third position of said manual means closing said second switch, switch position indicating means for at will moving said manual means back and forth between first and second and between second and third positions, the movement of said last-mentioned means from first or third position to second position opening the first switch if closed and repositioning the automatic means for a subsequent automatic switch closing operation if not in such position.

9. An alarm clock combination comprising a clock, an audible alarm, first and second switches for controlling a circuit, automatic means operated by said clock for starting and stopping said audible alarm and for closing the first switch, movable manual means accessible at the front of said clock for adjusting said automatic means to cause said automatic operations to occur at predetermined desired times and at will to permit or prevent the sounding of said audible alarm

without interfering with said automatic switch closing operation, another movable manual means accessible at the front of said clock to, at will, permit or prevent the automatic closing operation of said first switch without interfering with said automatic audible alarm operations and to, at will, open said first switch if closed and recondition its automatic closing means for a subsequent automatic closing operation if not in such condition, said last-mentioned manual means serving also to open and close the second switch and having the same position for the open condition of the second switch as that for preventing automatic closing operation of the first switch.

DAVID L. BOHMAN.
